Patented Mar. 17, 1970

216,901

EGG-SHAPED TOY FIGURE

Reuben B. Klamer, 245 Barrington Ave.,
Los Angeles, Calif. 90049

Filed Aug. 2, 1967, Ser. No. 8,097

Term of patent 14 years

Int. Cl. D21—02

U.S. Cl. D34—2

FIG. 1

FIG. 2

FIGURE 1 is a view in perspective showing the egg-shaped toy figure design of the invention; and,

FIGURE 2 is a rear perspective thereof.

I claim:

The ornamental design for an egg-shaped toy figure, substantially as shown.
